CLAIM

The ornamental design for a beverage capsule holder, as shown and described.

DESCRIPTION

FIG. 1 is a perspective view of a beverage capsule holder showing the new design;

FIG. 2 is a front view of the beverage capsule holder of FIG. 1;

FIG. 3 is a rear view of the beverage capsule holder of FIG. 1;

FIG. 4 is a bottom view of the beverage capsule holder of FIG. 1;

FIG. 5 is a left side view of the beverage capsule holder of FIG. 1;

FIG. 6 is a top view of the beverage capsule holder of FIG. 1;

FIG. 7 is a right view of the beverage capsule holder of FIG. 1;

FIG. 8 is a perspective view of the beverage capsule holder shown in an open position in an environment of use;

FIG. 9 is a bottom perspective view of the beverage capsule holder of FIG. 1 wherein the drawer is in an open position;

FIG. 10 is a top view of the drawer of the beverage capsule holder isolated for clarity of the disclosure; and,

FIG. 11 is a side view of the drawer of the beverage capsule holder isolated for clarity of the disclosure.

The broken lines representing a cocktail machine and beverage capsules shown in FIG. 8 depict environment and form no part of the claimed design.

1 Claim, 7 Drawing Sheets
